UNITED STATES PATENT OFFICE.

MILTON DORN, OF TELFORD, PENNSYLVANIA.

JAR-CLOSURE.

1,261,782.

Specification of Letters Patent.

Patented Apr. 9, 1918.

Application filed June 1, 1916. Serial No. 101,069.

To all whom it may concern:

Be it known that I, MILTON DORN, a citizen of the United States, residing at Telford, in the county of Montgomery, State 5 of Pennsylvania, have invented a new and useful Jar-Closure; and I do hereby declare the following to be a full, clear, and exact description of the invention, such as will enable others skilled in the art to which it applies to make and use the same.

This invention relates to the art of jars and closures therefor, and more especially to an opening including a closure for the jar closure.

15 One of the objects of the invention is to provide a simple, improved, essential and practical closure for an opening, particularly adapted for preventing breaking of the vacuum in a jar, such as those that are used 20 for the preservation of various food products, such as preserves or fruits, certain vegetables and the like.

Another object of the invention is the provision of an opening having a surrounding flange or raised portion, which is engaged by a rubber disk or the like, in combination with a transverse wire clamp, the side wire arms of which engage the rubber disk or the like so as to hold the same down 30 on both sides of the raised portion or flange, thereby preventing the exterior atmosphere from entering the opening, which would break the vacuum.

In practical fields the details of construction may necessitate alterations falling within the scope of what is claimed.

The invention comprises further features and combination of parts as hereinafter set forth shown in the drawings and claimed.

40 In the drawings:—

Figure 1 is a view in perspective of the improved closure for the opening of a preserving jar closure, constructed in accordance with the invention.

45 Fig. 2 is a sectional view on line 2—2 of Fig. 1.

Fig. 3 is a sectional view on line 3—3 of Fig. 1 at right angles to Fig. 2.

Fig. 4 is a detail view of the closure described.

Referring more especially to the drawings 1 designates a portion of a preserving jar, and 2 the usual jar closure, which is provided with the usual glass plate adjacent the 55 under surface of the top of said closure. In

terposed between the jar closure and the jar is the usual rubber gasket 3. Extending through the metal top of the jar closure, that is, through an opening 4 thereof, is a metal bushing 5, the upper portion of which forms 60 a rib 6 or flange, while the reduced part 7 of the bushing passes through the metal wall of the jar closure, and through an opening 8 of the glass plate 9. The side of the jar closure is provided with a short socket 10, 65 into the ends of which, the bent ends 11 of the sides 12 of the wire clamp 13 pivotally engage. This wire clamp is constructed from a single length of wire bent upon itself as shown at 14, thereby forming the two 70 sides. Where the single length of wire is bent upon itself, a loop is formed, which in itself is bent, to provide a hook, which engages the metal jar closure at a point diametrically opposite where the clamp is 75 hinged. As will be noted the sides of the wire clamp are bowed downwardly correspondingly and are so spaced relative to each other as to partially engage down upon adjacent opposite sides of the flange about 80 the opening, so as to hold a rubber gasket or disk 16 snugly in engagement with said flange, thereby preventing the exterior atmosphere from entering the opening and breaking the vacuum in the jar. This rubber gasket or disk 16 at diagrammatically opposite points is provided with incisions or 85 slots 17, through which the clamp passes in the manner shown in the drawing. The slots or incisions 17, particularly one of 90 them, through which the sides 12 of the clamp passes act to hold the bent ends 11 of the sides 12 in the socket 10 of the jar closure, thereby preventing disconnection of the clamp. The bowing or bending of the 95 sides of the clamp downwardly acts as yieldable means, to insure pressure upon the rubber gasket or disk.

It will be seen that this invention greatly facilitates the opening of jars, which is often 100 times a difficult matter.

The vent and closure clamp and disk being so constructed that when it is desired to open the jar the rubber disk can be easily removed from the vent thus admitting the 105 outside air into the jar; this breaks the vacuum and so reduces the pressure of the cap on the rubber ring and thus makes it much easier to unscrew or remove cap from the jar.

The invention having been set forth what is claimed as new and useful is:—

In combination with a jar closure having a central flanged vent and provided on its side with a bulge concentric with the closure, said bulge having an opening, a clamp consisting of a single piece of yieldable wire bent upon itself to form a loop at one end of the clamp bent downwardly to engage the closure, the arms of said loop having right angle parts at their extremities, said right angle parts terminating in lateral portions engaging the opening of the bulge, and a flexible disk gasket bearing upon the flanged vent and carried by the clamp whereby the

arms thereof may press the gasket down about all points of the marginal edge of said flange, said gasket having diametrically oppositely disposed slits through which the clamp passes, whereby the arms of the clamp are prevented from spreading and their lateral parts disengaging the opening of the bulge. 25

In testimony whereof I have signed my name to this specification in the presence of 25 two subscribing witnesses.

MILTON DORN.
